NAUTICAL CHART LOGGING TAPE CASING

John Fedoruk, 1215 5th Ave.,
New York, N.Y. 10029

Filed May 18, 1966, Ser. No. 2,342

Term of patent 14 years

(Cl. D52—1)

FIG. 1

FIG. 2

FIG. 3

FIG. 4

FIG. 1 is an end elevational view of the nautical chart logging tape casing embodying my new design;

FIG. 2 is a plan view;

FIG. 3 is a side elevational view; and

FIG. 4 is an end elevational view.

The opposite sides of FIGS. 2 and 3 are the same, in appearance, as the sides shown.

I claim:

The ornamental design for a nautical chart logging tape casing, as shown and described.
